Primary Examiner — Mimosa De(57) **CLAIM**

The ornamental design for a chair, as shown and described.

DESCRIPTION

FIG. 1 is a perspective view of the chair from a first point of view.

FIG. 2 is a perspective view of the chair from a second point of view.

FIG. 3 is a front view of the chair.

FIG. 4 is a back view of the chair.

FIG. 5 is a right side view of the chair.

FIG. 6 is a left side view of the chair.

FIG. 7 is a top view of the chair; and,

FIG. 8 is a bottom view of the chair.

Broken lines are also for illustrative purposes only and form no part of the claimed design.
